United States Patent Office

Des. 181,051
Patented Sept. 24, 1957

181,051

GAME BOARD

Arthur Harris, Brooklyn, N. Y.

Application March 27, 1956, Serial No. 40,797

Term of patent 7 years

(Cl. D34—5)

Fig. 1.

Fig. 2.

Fig. 1 is a top plan view of a game board showing my new design; and

Fig. 2 is a front elevational view thereof partially broken away at the right end.

The essential features of my design reside in the portions shown in solid lines on the drawing.

I claim:

The ornamental design for a game board, as shown and described.
